UNITED STATES PATENT OFFICE.

WILLIAM BICCRSTAFFE MONK, OF BIRMINGHAM, ENGLAND, ASSIGNOR TO THE DUNLOP RUBBER COMPANY, LIMITED, OF REGENT'S PARK, LONDON, ENGLAND, A BRITISH COMPANY.

FEEDING APPARATUS FOR USE IN CONJUNCTION WITH CUTTING MACHINES.

Application filed February 6, 1923. Serial No. 617,377.

To all whom it may concern:

Be it known that I, WILLIAM BICCRSTAFFE MONK, a subject of the King of Great Britain, residing at Fort Dunlop, 5 Erdington, Birmingham, in the county of Warwick, England, have invented certain new and useful Improvements in or Relating to Feeding Apparatus for Use in Conjunction with Cutting Machines, of which 10 the following is a specification.

This invention relates to apparatus of the kind in which sheet canvas or other similar material is unwound from a roll or spool and fed or supplied to a cutting machine of the vertical bias or other type wherein the sheet material is cut into strips of the desired width ready for use in the manufacture of pneumatic tyre covers or casings. In a usual construction of apparatus of this 15 kind the material, wound on a stock roll removably mounted in the apparatus is unwound by means of positively driven feed rollers and during the unwinding, the material passes over and frictionally rotates a 20 removably mounted roll on which a lining cloth wound between the convolutions of the material on the stock roll is rebatched or wound. The material in passing from the feed rollers to the cutting machine hangs 25 from the feed rollers in the form of a loop (hereinafter referred to as the stock loop) from which the material is intermittently taken up by the feed device of the cutting machine. After the material on the stock 30 roll has been unwound and the re-batching roll for the lining fully loaded, these rolls are removed and replaced by a full stock roll and an empty or unloaded re-batching lining roll; this operation necessitates stop- 35 page of the cutting machine whose output is therefore restricted. In practice the feed from the stock roll must be slightly in excess of the requirements of the cutting machine so that an adequate supply of material 40 is always available in the stock loop and for this reason when the said loop is full the supply from the positively driven feed rollers has to be stopped for which purpose hand operated clutch mechanism is pro- 45 vided for disconnecting the feed rollers from their driving means so that the stock 50

loop can be reduced by the supply to the cutting machine; when the stock loop is reduced to its minimum the feed rollers have to be connected to the driving means 55 in order to supply more material to the stock loop. This arrangement is disadvantageous for the reason that the whole attention of an operator is required in manipulating the clutch mechanism to control the 60 supply of material to the stock loop. The chief objects of the present invention are to avoid interruption in the operation of the cutting machine when removing and replacing the stock rolls and to avoid the 65 necessity of an operator for controlling the supply of material to the stock loop.

According to this invention two stock rolls are provided so that as soon as the material has been fully unwound from one 70 stock roll the material from the other stock roll can be used to continue the supply, the said rolls being so supported as to permit of an empty stock roll being removed whilst the material is being unwound from the 75 other stock roll. The two stock rolls are removably supported at different heights in centres or bearings in the main frame, and a lining re-batching roll supported in 80 centres or bearings in the said frame is associated with each stock roll so that it can be frictionally rotated by the material being unwound from its corresponding stock roll, in order to wind up or re-batch the lining 85 which is unwound with this material. Although the lining rolls are frictionally rotated to wind up the lining they have associated therewith independent clutch mechanisms which can be operated to connect the 90 lining rolls with common driving mechanism so that either lining roll may be positively rotated in order to wind up the surplus lining which precede and follows the length of material wound on each stock roll. During the unwinding of the material from 95 one stock roll and the winding up of the lining on the corresponding lining roll, the other and empty stock roll and its corresponding full or loaded lining roll are removed and replaced by a full stock roll and 100 an empty lining roll ready for the leading end of the material on the full stock roll to

be joined to the rear end of the material from the other stock roll when fully unwound. A table may be provided adjacent to the positively driven feed rollers to support the ends of the material when being joined as aforesaid. By means of this invention removal and replacement of the stock rolls and the lining rolls and the joining of the ends of the material as above set forth can be effected without interrupting the operation of the cutting machine.

According to a further feature of this invention automatic means are provided for controlling the operation of the feed rollers that supply the material to the stock loop so that the latter can be entirely regulated by the automatic means. For this purpose the stock loop may carry a roller, bar or the like which when the stock loop is filled actuates clutch mechanism in such manner as to disconnect the driving means for the feed rollers from the operating shaft, so that the feed rollers are not operated and do not draw the material from the stock rollers; the material however is drawn from the stock loop by the feed device of the cutting machine and when the stock loop is reduced to its minimum the said roller or bar carried by the stock loop actuates the clutch mechanism so that the feed rollers may be operated to supply more material from the stock rollers to the stock loop.

According to a further feature of the invention an improved feeding device is provided for supplying the material from the stock loop to the cutting machine whereby a more efficient and more positive gripping surface is obtained, thus resulting in greater accuracy in the width of the cut. For this purpose a series of narrow endless belts or bands are passed around an intermittently driven feed roller of the cutting machine and a roller supported in a lower position so as to form an inclined multiple belt conveyor which is intermittently operated to supply or draw the material from the stock loop so that it travels over the several belts or bands and is conveyed to the knife of the cutting machine.

In order that the invention may be clearly understood and readily carried into effect the same will now be described more fully with reference to the diagrammatic accompanying drawings, in which:—

Figure 1 is a general perspective view of one construction of the apparatus embodying the improvements according to this invention and showing more particularly the disposition of the stock rolls and lining rolls.

Figure 2 illustrates the paths of the material from the stock rolls to the feed rollers and the stock loop.

Figure 3 is a perspective view showing more particularly the automatic means for

controlling the driving mechanism of the feed rollers which supply the material to the stock loop.

Figure 4 is an elevation of part of the said automatic means shown in Figure 3.

A represents one stock roll and B indicates the lining roll which is frictionally driven or rotated by the material A¹ as it is unwound from the stock roll A so that the lining B¹ which is unwound with the material A¹ can be wound or re-batched on to the said lining roll B. C represents the other stock roll and D indicates the lining roll to receive the lining D¹ which is unwound with the material C¹ from the stock roll C, the rotation of this lining roll D being effected by the material C¹ passing over the same. E and F represent the feed rollers which are positively driven by suitable driving mechanism hereinafter referred to for unwinding the material A¹ or C¹ from the stock rolls A or C, to form the stock loop G, from which the material is supplied to the feeding device H of the cutting machine which may be of any suitable or usual kind. The stock rolls A and B are removably mounted at different heights in centres or bearings in the side portions of the main frame I, the two centres or bearings on one side of the said frame being controlled by band brakes A² and C² which can be regulated as required during the unwinding of the material A¹ and C¹ from the said stock rolls. The lining rolls B and D are also removably mounted in centres or bearings in the main frame I so as to be frictionally rotated by the material as aforesaid and the centres at one side of the frame I are provided with independent hand controlled clutch mechanisms B² and D² comprising rotary clutch members driven by chains B³ and D³ from sprockets B⁴ and D⁴ on a shaft J¹ rotated by chain gearing J² from a main driving shaft J hereinafter referred to.

By means of the clutch mechanisms B² and D² either of the lining rolls may be connected to the aforesaid rotary shaft J¹ and positively rotated at a high speed for quickly winding up the surplus lining material which precedes and follows each length of material A¹ or C¹ on the stock rolls A or C; otherwise the lining rolls B and D are frictionally driven by the material A¹ or C¹ when the latter is being unwound from the stock rolls by the positively driven feed rollers E and F. Assuming that the material A¹ is being unwound from the stock roll A, it first passes over the lining roll B to rotate the latter and then around guide rolls A³ whence it travels over a table A⁴ (see Figure 2) so as to pass under the lower feed roller F and around the upper one E from which the material is suspended to form the stock loop G that provides the necessary surplus of material to be drawn

110

intermittently by the feeding device H which conveys the material to the knife of the cutting machine. After the material A¹ has been fully unwound from the stock 5 roll A and its lining material B¹ completely re-batched or wound on the roll B the leading end of the material C¹ from the stock roll C is passed over the lining roll D around guide rollers C² as shown by the dotted lines 10 in Figure 2 and then around the guide rollers A³ A³ so that it can be joined in any suitable manner to the rear end of the unwound material A¹ whilst supported on the table A⁴. The material C¹ is therefore ready 15 to be drawn between the feed rollers E F to form the stock loop G and during this operation the loaded or fully re-batched lining roll B is removed from its centres in the main frame and the empty stock roll A is transferred to these centres so as to serve 20 as the re-batching roll for the lining of a full stock roll which is placed in the centres from which the previous and empty stock roll A was removed. The surplus lining in 25 advance of the material on the full stock roll is wound quickly on to the new lining roll by connecting this roll to the rotary shaft J¹ through the clutch mechanism B² so that the leading end of the material on 30 the full stock roll is ready to be attached to the rear end of the material C¹ as soon as this material C¹ has been completely unwound from the stock roll C. After the material C¹ has been unwound and its lining 35 D¹ re-batched on the roll D the leading end of the material on the full stock roll is attached to the rear end of the material C¹ whereupon the loaded lining roll D is removed from its centres, in which the empty 40 stock roll C is then placed to serve as the re-batching roll for the lining on a fully loaded stock roll which is placed in the centres vacated by the empty stock roll C. By this arrangement practically no time is lost 45 in the removal and replacement of the stock rolls and the lining rolls so that a practically continuous operation of the cutting machine can be effected.

As shown in Figure 1 the feed rollers E and F are geared together by pinions E¹ and F¹, the upper roller F being provided with a sprocket operatively connected by a chain E² to a sprocket E³ (see Figures 3 and 4) loosely mounted on the driving shaft J but adapted to be connected to the said shaft by a rotary clutch E⁴ slidably keyed on said shaft J. The clutch E⁴ is slidably moved by a suitably pivoted or forked lever E⁵ into and out of engagement with a clutch member formed on the loose sprocket E³ the said lever E⁵ being actuated by mechanism which is automatically operated by the stock loop as hereinafter described. The shaft J is continuously rotated for example 50 by means of a belt drive J² through varia-

ble speed friction gear J⁴ comprising a large driving disc that rotates a smaller disc whose position in relation to the centre of the larger disc can be varied by adjusting means J⁵, the smaller disc transmitting the 55 rotation to bevel gearing J⁶ which rotates the shaft J. The said variable speed friction gear permits of variation in the feed from the stock rolls to suit the requirements of the cutting machine as regards various 60 widths of material to be cut. In order that the stock loop may be automatically controlled a heavy roller G¹ see Figures 3 and 4 is "threaded in" or suspended by the said loop G with its ends slidably fitted in vertical guides or channels G² in such manner that the roller G¹ may be raised or lowered by the stock loop as the latter diminishes or increases. One end of the said roller G¹ is adapted to come into contact with one or 65 other of a pair of trip levers G³ and G⁴ on reaching the limits of its upward and downward movements. These trip levers are connected to a vertical rod G⁵ which by means of pins G⁶ thereon engages with one 70 end of a bell crank lever G⁷ pivoted on a suitable part of the main frame, the other end of the said bell crank lever being articulated to the lower end of a lever G⁸ centrally pivoted on the main frame at a point directly above the pivot of the bell crank lever G⁷. The upper and free end of the lever G⁸ is connected to the pivot pin of the bell crank lever G⁷ by a tension spring G⁹. The articulated ends of the bell crank lever G⁷ and the lever G⁸ are suitably connected to a horizontal bar E⁶ slidably mounted in a guide E⁷ and pivoted to the upper end of the lever E⁵ which moves the clutch member E⁴ into and out of engagement with the 75 clutch member on the loose sprocket E³ that is operatively connected by the chain E² to the sprocket on the upper feed roller E. When the stock loop G is filled, the roller G¹ depresses the lower trip lever G⁴ which 80 raises the vertical rod G⁵ so as to rock the bell crank lever G⁷ and the lever G⁸ and thus cause the bar E⁶ to be pushed outwardly and to move the pivoted lever E⁵ outwardly so that the clutch member E⁴ is disengaged 85 from the clutch member on the sprocket E³; the parts are retained in this position by the tension spring G⁹. The rotation of the shaft J is therefore not transmitted to the feed rollers E and F and the material is drawn from the stock loop into the cutting machine as required by the intermittently operated feed device H so that the loop diminishes and raises the roller G¹. Upon the stock loop being practically reduced to its 90 minimum the said roller G¹ actuates the upper trip lever G³ which therefore depresses the vertical rod G⁵ which in turn rocks the bell crank lever G⁷ and the lever G⁸ in order to slide or pull the horizontal bar E⁶ inward-

4
ly so that the forked lever E⁵ is actuated to place the clutch E⁴ into engagement with the clutch on the loose sprocket E³ thereby enabling the drive to be transmitted from the shaft J to the upper feed roll by the sprocket chain E². The tension spring G⁹ also retains the parts in this position; two notches E⁸ are provided in the bar E⁶ so as to be engaged by a stop roller E⁹ in the aforesaid guide E⁷ in order to definitely locate the bar E⁶ in either of its two positions. The feed device which is represented generally by the reference letter H comprises a series of narrow endless belts H¹ that pass around a lower roller H² and an upper roller H³ which latter is intermittently driven in any suitable manner to impart the required movement of the belts H¹ which draw the material from the stock loop and carry it around the upper feed roller H³ whence the material is supplied vertically to the inclined knife that cuts the material on the bias. The multiple belt conveyor formed by the belts H¹ enables the grip or friction on the material to be considerably increased with the result that a satisfactory feed is obtained which ensures greater accuracy in the width of the cut.

What I claim and desire to secure by Letters Patent of the United States is:—

1. Apparatus for supplying sheet canvas or similar material to a cutting machine, comprising a single frame work for supporting a plurality of stock rolls and a plurality of lining rolls, one for each stock roll, means whereby each lining roll can be driven from its stock roll and also independently if desired, supporting means on which the rear end of the material unwound from one stock roll can be readily joined to the leading end of the material to be unwound from another stock roll, means whereby each stock roll when empty, together with its lining roll when full, can be removed and replaced by a full stock roll and an empty lining roll whilst the material is being drawn from the other stock roll and automatic means interposed between the stock rolls and a conveyor that supplies the material to the cutting machine, for controlling the unwinding of the stock material from either stock roll and ensuring a predetermined adequate supply of material at the position where it is taken up by the conveyor according to the requirements of the cutting machine.

2. Apparatus for supplying sheet canvas or similar material to a cutting machine, comprising a plurality of stock rolls, means for removably supporting the same in the main frame of the apparatus a lining roll associated with each stock roll, means for removably supporting the lining rolls in the said main frame in such manner that each lining roll can be frictionally rotated by the

material that is unwound from the corresponding stock roll so as to wind up the lining which is unwound with this material, and clutch mechanism associated with each lining roll for connecting either of lining rolls to a common driving means and enabling the same to be positively rotated to quickly wind up the surplus lining that precedes and follows each length of material on the stock rolls.

3. Apparatus for supplying sheet canvas or similar material to a cutting machine, comprising a single frame work for supporting a plurality of removable stock rolls and a plurality of removable lining rolls, one for each stock roll, guide rollers over which the material from either stock is drawn, common feed rollers for drawing the material from either stock roll, means whereby the lining rolls can be frictionally driven by the stock material or can be independently driven when desired, and a table positioned between the said guide rollers and the feed rollers, on which table the rear end of the material unwound from one stock roll can be joined to the leading end of the material which is to be unwound from the other stock roll.

4. Apparatus for supplying sheet canvas or similar material to a cutting machine, comprising a plurality of stock rolls and a plurality of lining rolls, one for each stock roll, a frame in which all said rolls are removably supported, common feed rollers in said frame which are positively rotated to unwind the material from either stock roll and supply it to a stock loop, means for drawing the material from the stock loop and supplying it to the cutting machine, means for frictionally or positively driving said lining rolls, and automatic means operated by the stock loop for controlling the operation of the said common feed rollers and enabling the material to be drawn from either stock roll according to the requirements of the stock loop.

5. Apparatus for supplying sheet canvas or similar material to a cutting machine, comprising a frame supporting a stock roll and a lining roll at a position above a second stock roll and lining roll, means whereby said stock rolls and lining rolls can be readily removed from the frame, guide rollers in said frame over which the material from either stock roll passes, a support on which the rear end of the material unwound from one stock roll can be connected to the leading end of the material to be unwound from the other stock roll, feed rollers located in said frame at a position beyond the said support, a conveyor device beyond said feed rollers, means for forming a loop of the stock material between the said feed rollers and the conveyor device, a controlling member movable by said stock loop, and means operable

by said controlling member for connecting or disconnecting the feed rollers to or from a driving shaft.

6. Apparatus for supplying sheet canvas or similar material to a cutting machine, comprising a frame supporting a stock roll and a lining roll at a position above a second stock roll and lining roll, means whereby the said rolls can be readily removed from 5 said frame, guide rollers in said frame over which the material from either stock roll passes, means on which the rear end of the material from one stock roll can be connected to the leading end of the material on 10 the other stock roll, feed rollers located in said frame at a position beyond the said table, a conveyor device beyond said feed rollers, means for forming a loop of the stock material between the said rollers and the conveyor, a controlling member vertically movable in guides by said stock loop, trip levers in the path of and adapted to be engaged by said controlling member, a vertical rod 15 movable by said trip levers and adapted to impart endwise movement to a horizontal rod, a rotary clutch member operated by said horizontal rod and slidably keyed on a driving shaft for connecting or disconnecting this shaft to driving means that rotate 20 the said feed rollers.

7. Apparatus for supplying sheet canvas or similar material to a cutting machine, comprising a plurality of stock rolls, a plurality of lining rolls, one for each stock roll, positively rotated feed rollers for drawing the material from either of the stock rolls to form a stock loop, all of said rolls and rollers being mounted in the same frame, means controllable by the size of the stock loop for 25 connecting or disconnecting the feed rollers to and from a driving shaft, an intermittently operated device for supplying the material from the stock loop to the cutting machine, and variable speed mechanism for 30 varying the speed of rotation of the feed roller driving shaft to suit the requirements of the cutting machine as regards various widths of the material to be cut.

8. Apparatus for supplying sheet canvas or similar material to a cutting machine, comprising a frame supporting a plurality of stock rolls, a plurality of lining rolls, one for each stock roll, means for frictionally driving the line rolls, means for connecting the line rolls to said driving means, feed rollers for drawing the material from either of the stock rolls to form a stock loop, a conveyor device for taking up material from the stock loop and supplying it to the cutting machine, a driving shaft for operating said feed rollers, a sprocket loosely mounted on said shaft and connected by a chain to a sprocket on one of the feed rollers, a clutch 55 for coupling said loose sprocket to the shaft, a vertically movable bar suspended in said 60

stock loop, trip mechanism operable by said stock loop bar, and means operated by said trip mechanism for slidably moving said clutch into or out of engagement with said loose sprocket.

9. Apparatus for supplying sheet canvas or similar material to a cutting machine, comprising a single frame for supporting a plurality of stock rolls, a plurality of lining rolls, one for each stock roll, feed rollers 70 for drawing the material from either of the stock rolls to form a stock loop, an intermittently operated device for supplying the material from the stock loop to the cutting machine, a driving shaft for operating said feed rollers through chain and sprocket gearing, a clutch for operatively connecting said gearing to the said shaft, a vertically movable bar suspended in said stock loop, trip mechanism operable by said stock loop bar, means operated by said trip mechanism 75 for slidably moving said clutch into or out of engagement with said sprocket gearing and variable speed mechanism for driving said feed roller driving shaft.

10. Apparatus for supplying sheet canvas or similar material to a cutting machine, comprising a single frame for supporting a plurality of removable stock rolls, a plurality of removable lining rolls, one for each stock roll, common feed rollers for drawing the material from either stock roll, guide rollers over which the material from either stock roll passes so as to frictionally rotate the lining roll for the operative stock roll, a table over which the material passes prior to reaching the feed rollers and on which the rear end of the material unwound from one stock roll can be attached to the leading end of material to be unwound from another stock roll, means for positively driving the lining rolls when required, means whereby the feed rollers form a stock loop, means for drawing the material intermittently from the stock loop, and means operable by the stock loop for disconnecting or connecting the feed rollers from their driving means.

11. Apparatus for supplying sheet canvas or similar material to a cutting machine, comprising a single frame for supporting a plurality of removable stock rolls, a plurality of removable lining rolls, one for each stock roll, feed rollers for drawing the material from either stock roll, guide rollers over which the material from either stock roll, passes so as to frictionally rotate the lining roll for the operative stock roll, a table over which the material passes prior to reaching the feed rollers and on which the rear end of the material unwound from one stock roll can be attached to the leading end of material to be unwound from another stock roll, means for positively driving the lining rolls 115 when required, means whereby the feed 120

125

130

8
rollers form a stock loop, means carried by the stock loop for engaging arms on a vertical movable rod, a horizontal rod operated by said vertically movable rod, a lever connection from the horizontal rod for moving a clutch slidable on and rotatable with a driving shaft, a loose sprocket on said shaft connected by a chain to a sprocket on one of the feed rollers, and variable speed mecha-

nism for rotating said driving shaft, which, 10 when said clutch engages said loose sprocket, enables material to be supplied by the feed rollers to the stock loop, from which the material is drawn by an intermittently operated multiple belt conveyor that supplies 15 it to the cutting machine.

WILLIAM BICCERSTAFFE MONK.
